UNITED STATES PATENT OFFICE

91,290

DESIGN FOR A RADIOCABINET OR THE LIKE

Everett Worthington, Chicago, Ill., assignor to
The Stromberg-Carlson Telephone Manufacturing Company, Rochester, N. Y., a corporation of New York

Application November 10, 1933
Serial No. 49,697

Term of patent 3½ years

To all whom it may concern:

Be it known that I, EVERETT WORTHINGTON, a citizen of the United States, residing at Chicago, in the county of Cook and State of Illinois, have invented a new, original, and ornamental Design for Radiocabinets or the like, of which the following is a specification, reference being had to

the accompanying drawing, forming part thereof.

The single figure is a front perspective view showing my new design.

I claim:

The ornamental design for a radiocabinet or the like, as shown.

EVERETT WORTHINGTON.
